UNITED STATES PATENT OFFICE

CARL GEORG MUNTERS, OF STOCKHOLM, SWEDEN, ASSIGNOR TO ELECTROLUX SERVEL CORPORATION, OF NEW YORK, N. Y., A CORPORATION OF DELAWARE

REFRIGERATION

Application filed August 28, 1926, Serial No. 132,160, and in Germany July 26, 1926.

My invention comprises novel advances in the art of treatment of gas and vapor, especially applicable to refrigeration producing processes, particularly the absorption process. The objects of the invention include the obtaining of higher efficiency than previously has been known in processes to which the invention is applicable; the automatic regulation of liquid and gas separation by inherent process characteristics; automatic self-regulating adjustment of process steps to proper co-ordination with differing loads and heat balances; and others apparent as the description proceeds.

In one important phase of the invention, vapor is expelled from a solution, condensed and then reheated to revaporation by the primary generation for the purpose of condensing a portion of the primary vapor. I have developed various characteristic novel processes, process steps and apparatus involving this principle as will presently be apparent. Besides the above my invention contemplates further improvements and novel combinations in process and apparatus.

Various manners of carrying out my invention are shown on the accompanying drawings of which:

Fig. 1 is a view partly in elevation and partly in section of parts of a refrigerating apparatus;

Fig. 2 is a sectional view taken on the line 2-2 of Fig. 1, parts being shown in full;

Fig. 3 is a section taken on the line 3-3 of Fig. 1;

Fig. 4 is a section taken on the line 4-4 of Fig. 1;

Fig. 5 shows diagrammatically a different form of refrigerating apparatus showing a further development of the invention beyond what is included in the apparatus of Figs. 1-4;

Fig. 6 is a view partly in section of another apparatus in accordance with this invention;

Fig. 7 is a sectional view taken on line 7-7 of Fig. 6;

And Fig. 8 shows diagrammatically the

invention in one embodiment, applied to an absorption refrigerating machine of known type employing a pump.

Referring more particularly to Fig. 1, which shows an apparatus of the constant equalized pressure type, 10 designates a generator which contains a solution 11 of cooling agent or refrigerant in a solvent. In forms of the invention herein described I shall designate ammonia as the cooling agent, water as the solvent or absorption liquid and hydrogen as an auxiliary medium into which ammonia diffuses for the purpose of evaporation. It is to be understood, however, that the selection of these substances is for the purpose of illustration and without limitation.

Heat is applied to generator 10 by means of an electric heating element 24 which sets into a pocket 25 in the bottom of the generator. Ammonia vapor expelled from solution in the generator passes through conduit 12 and into a device which I herein term a reheat-separator. The reheat-separator is designated generally by reference character 20. It is simultaneously a heat exchanger, a boiler, a condenser, a regulator and a separator. In the reheat-separator, steam which is entrained with the ammonia vapor passing through conduit 12 is condensed so that it may flow back toward the generator and so that it will not pass on through further parts of the refrigerating apparatus. The reheat-separator comprises an outer shell 13 and an inner conduit 17. Between parts 13 and 17 there is a first path 29 for flow of ammonia vapor. Conduit 17 constitutes a second path for the flow of ammonia as will presently be explained. In the first ammonia path 29 is a series of baffling members 21, 22. Fig. 3 shows a baffling member 21. Fig. 4 shows a baffling member 22. Baffling member 21 has a side aperture 26 on one side and baffling member 22 has a side aperture 27 on the opposite side. Alternate baffling members are of type 21 and intermediate alternate baffling members of type 22. Apertures 26 and 27 are thus placed out of alignment to give a tor-

70

100

tuous path for ammonia through the reheat-separator and this tortuous flow aids in the separation of entrained water vapor. The reheat-separator is inclined downwardly toward the generator and each of disks 21 and 22 is equipped with a lower opening 28 so that condensed water vapor flows backward through the passageway formed by openings 28 toward the generator.

10 Ammonia vapor after passing through the reheat-separator continues through conduit 14 and into condenser 15. Condenser 15 comprises a pipe coil surrounded by a water jacket 16 but it is to be understood that the 15 condenser as well as other parts of the apparatus may be made of various constructions. Condenser 15 is connected with conduit 17. Ammonia is condensed in condenser 15 and passes into conduit 17. The ammonia in 20 conduit 17 is colder than the vapor in path 29 and there consequently occurs a transfer of heat from path 29 into path 17. Ammonia vapor entering path 29 contains superheat and it loses some or all of its superheat due to the cooling effect of condensed 25 ammonia in conduit 17. To illustrate, in an apparatus built according to this invention the temperature of ammonia gas and entrained water vapor leaving the generator 30 may be 275° F. with a pressure of 242 lbs. The proportion by weight of water to the total quantity of ammonia and steam is about 14%. In its passage through the reheat-separator the temperature of the ammonia and entrained water vapor is reduced 35 from 275° F. to about 113° F. This last temperature is somewhat higher than the saturation temperature at 242 lbs. At this reduced temperature the water vapor entrained is practically entirely condensed and the amount of water remaining in vapor form and passing into the condenser through 40 conduit 14 is only a few hundredths of one percent of the amount by weight of fluid passing into the condenser. The condensed water absorbs some ammonia as it passes back toward the generator. In its passage back toward the generator, it passes through 45 increasingly hotter zones and the increase in temperature causes the ammonia to be again 50 expelled from the condensate until, by the time the separated condensate has completed its return through the reheat-separator, its temperature and its ammonia concentration 55 is substantially the same as that in the generator. The fluid entering condenser 15, which is practically pure ammonia, is cooled, decreased in temperature to the saturation temperature at the existing pressure and is 60 condensed, and is further cooled some degrees below the saturation point. All that is necessary, however, is to reach the saturation temperature in condenser 15 and obtain condensation sufficient for the subsequent 65 revaporation in conduit 17 to condense the

entrained water in path 29. The ammonia entering conduit 17 from condenser 15 is revaporized due to the higher temperature in path 29 and transfer of heat through conduit 17. As the ammonia is revaporized or evaporated in conduit 17 it draws heat from the surrounding hot vapor in path 29 so that the temperature of the vapor passing through path 29 more and more approaches the saturation temperature at which the ammonia in conduit 17 boils and thus is more and more freed of entrained water although it cannot reach this temperature wherefore no ammonia can be condensed in the reheat-separator. The revaporized ammonia in conduit 17 is again condensed in the second condenser 19 whereupon the condensate flows to the evaporator. From the second condenser 19 the ammonia passes through conduit 49 into evaporator 30.

Evaporator 30 forms a portion of what may be termed a local cycle including also absorber 31, a hydrogen conduit 32, and a mixture conduit 33. Hydrogen circulates through this local cycle. In the evaporator the ammonia diffuses into the hydrogen and evaporates thereby producing refrigeration. The mixture of ammonia and hydrogen vapor formed in the evaporator passes through conduit 33 and into absorber 31. In the absorber, ammonia is absorbed by absorption liquid supplied thereto through conduit 34. Hydrogen which is relatively free from ammonia passes through conduit 32 to the evaporator to again mix with ammonia. Since the mixture of hydrogen and ammonia in the evaporator is heavier than the gas in the absorber which is composed of hydrogen to a greater extent, an automatic circulation is produced through the evaporator and absorber. The evaporator and absorber are equipped with disks 35 containing passageways, which disks serve to give large surfaces of evaporation and absorption. The absorber is placed within cooling water jacket 16 and its upper portion constitutes a pre-cooling arrangement for weak absorption liquid entering the absorber from the generator.

Strong absorption liquid passes from the bottom part of the absorber through conduit 36 and into coil 37 which surrounds heating element 24 and is heated thereby. Thence the absorption liquid passes through conduit 38 and into the upper part of the generator. Weak absorption liquid flows through conduits 39, 40 and 34 into the absorber. Conduits 36 and 40 are placed in heat exchange relation. Coil 37 is an auxiliary generator which serves to circulate absorption liquid between the generator and absorber.

The various parts of the apparatus are maintained at the same constant total pres-

sure and all parts are in unobstructed communication with each other. The evaporator is placed within a brine tank or otherwise arranged within the place to be cooled. In Fig. 2 $\frac{5}{5}$ designates the wall of a room.

6 In Fig. 2, 75 designates the wall of a refrigerator cabinet, the evaporator being placed inside the cabinet and the absorber and generator outside wall 75 with respect to the cabinet.

10 In so far as the above described Figs. 1 to 4 are concerned, the invention is primarily directed to the reheat-separator and its relation to the apparatus as a whole. The specific local cycles between the generator and absorber and between the absorber and evaporator as shown in the above described figures are not a part of the present invention except in combination with the reheat-separator. As respects this matter 15 reference may be had to copending application Serial No. 130,086 filed on August 18, 1926 by Baltzar Carl von Platen and me jointly which has matured into Patent No. 20 1,609,384 granted December 7, 1926.

25 By means of the reheat-separator the apparatus is made independent of the quantity of fluid cycling through the same, that is, it is made independent of the intensity of heat supply. If the intensity of heat supply is increased, a greater part of conduit 17 becomes effective to cool the vapor in path 29. The whole arrangement automatically regulates itself independently of cooling water quantities and temperatures and other external factors. It is thus possible to operate the apparatus simply and automatically with constant efficiency at any load within the capacity of the apparatus.

load within the capacity of the apparatus.

40 In the embodiment shown in Fig. 5, a different form of reheat-separator is disclosed. The generator in this embodiment is indicated by reference character 10 as in Fig. 1. Whereas the generator of Fig. 1 was heated by electricity, the generator of Fig. 45 Fig. 5 is heated by gas supplied through a gas burner 41. The gases of combustion resulting from the operation of the gas burner pass through flue 42 within generator 10. Vapor expelled in generator 10 passes through conduit 43 which is extended so as to be cooled by air somewhat and to give a sufficient counter-flow path for expulsion of ammonia from the condensed solvent and also to prevent undesirable heat losses between the generator and the separator.

50

55

The reheat-separator is likewise designated by reference character 20 in this embodiment. It is arranged vertically and comprises an outer shell 44 and an inner member 45 which may be termed an evaporation or vaporization column. Evaporation column 45 is open at the top and there connects with the space 46 between the outer shell 44 and the evaporation column 45,

which space is the first path of ammonia through the reheat-separator. The space within evaporation column 45, designated by reference character 47, constitutes the second path of ammonia through the reheat-separator.

Conduit 14 connects the upper part of reheat-separator with condenser 15 which comprises a coil situated within cooling water jacket 16. Conduit 14 receives vapor both from path 46 and evaporation column 45.

The lower end of condenser coil 15 is connected to a separation chamber 51. Two conduits leave separation chamber 51, one conduit, 52, passing into the lower part of evaporation column 45 and the other conduit 53 passing upwardly and then downwardly with a loop at the top to connect with heat exchanger 55, hereinafter more fully described. Conduit 52 is connected to the bottom part of separation chamber 51 and is filled with liquid ammonia condensed in condenser 15. Conduit 53 is connected to the upper portion of separation chamber 51 so as to receive gas therefrom. The purpose of this gas separation chamber 51 and the conduit connection thereto is to separate from the ammonia any hydrogen gas which may have been entrained with the strong liquor passing from the absorber to the generator and carried along with the ammonia vapor expelled in the generator. The hydrogen gas passes through conduit 53 and into heat exchanger 55, this flow being caused by a very slight excess pressure developed by the generation process.

Liquid ammonia leaving the end of conduit 52 which is within evaporation column 45 is heated by superheated ammonia vapor in path 46 in manner similar to that explained with reference to the corresponding element of the apparatus of Fig. 1. This serves to condense water vapor entrained with the ammonia vapor expelled from the generator. In order to aid the transfer of heat from the vapor in path 46 to the liquid ammonia in evaporation column 45, a series of flanges 56 are provided which extend around evaporation column 45. In order to obtain a tortuous path of flow through path 46 a further series of flanges 57 is employed. The liquid ammonia within evaporation column 45 boils and wets the inner wall thereof for a considerable extent. 120

Vapor formed within evaporation column 45 passes out through the top thereof and into conduit 14. Obviously evaporation column 45 could have been connected to a separate condenser as conduit 17 of Fig. 1 is connected to condenser 19. By the arrangement shown in Fig. 5 the second condenser is eliminated and one condenser serves the function of condensing the ammonia vapor formed in both the initial stage

of vaporization and the reheating stage of vaporization.

Unevaporated liquid ammonia passes through the lower part of evaporation column 45 into conduit 58 which surrounds conduit 52. Conduit 58 is joined to U-shaped conduit 60 which passes downwardly from conduit 58, through conduit 61, horizontally through heat exchanger 55 and upwardly through conduit 62 into the upper part of the evaporator 30. Liquid ammonia is discharged from conduit 60 into evaporator 30 where it evaporates and produces refrigeration.

15 Heat exchanger 55 is composed of an outer cylindrical shell 63, two tube-heads 64 and 65, and a series of horizontal tubes 66.

20 Tubes 66 extend through apertures in heads 64 and 65 and connect end chamber 67 with end chamber 68. End chambers 67 and 68 are closed from central space 69 except for two small openings 70 and 71 in the bottom parts of tube-heads 64 and 65, 25 respectively.

End chamber 67 is connected with the upper part of absorber 31 by means of conduit 61. End chamber 68 is connected to the upper part of the evaporator 30 by means 30 of conduit 62. Hydrogen gas passes from the upper part of absorber 31, through conduit 61, through end chamber 67, through tubes 66, through end chamber 68, and through conduit 62 into the upper part of 35 the evaporator.

Central space 69 is connected with the bottom part of evaporator 30 by means of conduit 72 and this space is connected with the bottom part of absorber 31 by means of 40 conduit 73. The mixture of hydrogen gas and ammonia formed in the evaporator passes through conduit 72, through central space 69, around tubes 66 and around tube 60 and then through conduit 73 into the 45 lower part of the absorber where the ammonia is absorbed into absorption liquid and hydrogen is liberated from the mixture to return to the evaporator through the path hereinbefore traced, including conduit 61.

50 Since some vapor of the absorption liquid is entrained with the hydrogen passing through conduit 61 toward the evaporator, openings 70 and 71 are provided so that this entrained vapor of absorption liquid 55 which condenses on its way to the evaporator will drain into central space 69 and then return to the absorber. By this means the heat exchanger 55 and connected conduits are kept free of liquid.

60 By exchanging heat between the gas mixture in space 69 and the condensed ammonia in conduit 60 an appreciable gain in efficiency is obtained. The low temperature of the mixture serves to cool the hydrogen passing 65 into the evaporator and also to cool

the liquid ammonia passing into the evaporator. Thus, a low intake temperature exists in the evaporator and a higher thermal efficiency can be obtained. The quantity of gas mixture passing through 70 central space 69 for a given time is greater than the quantity of hydrogen passing through tube 66 for the same time wherefore there is sufficient cold in the gas mixture to cool the hydrogen and also to cool the 75 ammonia.

The hydrogen gas passing through conduit 53 enters central space 69 and is there mixed with the gas mixture and passes to the absorber through conduit 73. Obviously 80 conduit 53 need not be connected to space 69 but may, for example, be connected direct to the absorber.

The connections between the generator and the absorber are the same in Fig. 5 as 85 in the previous arrangement of Fig. 1. Like reference characters designate like parts, wherefore an explanation of this part of the apparatus is unnecessary in connection with Fig. 5.

Figs. 6 and 7 show one form of apparatus, as I would prefer to build it, embodying the present invention. The generator is again designated by reference character 10 and serves the same function, namely, to separate 90 ammonia or other refrigerant from solution. The ammonia vapor with entrained vapor of absorption liquid passes through conduit 43 and into the reheat-separator 20 which is made as a U-shaped member. The vapor 95 coming from the generator enters an outer cylinder 76. One leg 77 of a U-shaped tube extends within cylinder 76 and between members 76 and 77 is formed the first path 100 for fluid through the reheat-separator. This path is designated by reference character 29. Leg 77 of the U-tube corresponds to evaporation column 45 of Fig. 5. The second path through the reheat-separator is the space 105 within leg 77 which I have designated by reference character 47. A series of baffling ribs 56 surrounds members 77. The upper part of cylinder 76 is connected with condenser 15 by means of conduit 14. The upper end of leg 77 is open and is also connected with conduit 14 in the same manner as the corresponding part in Fig. 5. Condenser 15 consists of an inner ammonia conduit 78 surrounded by an outer water conduit 79. From condenser 15 liquefied 110 ammonia passes through conduit 80 which corresponds to conduit 52 of Fig. 5 and into the other leg 81 of the U-tube (see Fig. 7). The lower part of the U-tube is filled with liquid ammonia. Conduit 80 opens just 115 above the liquid ammonia in leg 81. Leg 81 extends upwardly and the upper portion is connected to a conduit 53, so designated because it corresponds to conduit 53 of Fig. 5. Entrained hydrogen passes through con-

duit 53 and into heat exchanger 55. Liquid ammonia boils in leg 77 and vaporizes and serves to condense entrained vapor of absorption liquid in path 29 causing the 5 entrained vapor in path 29 to fall downwardly to the bottom thereof wherefrom it returns through conduit 43 to the generator. Liquid ammonia passes from the lower part of the U-tube through conduit 10 60. Conduit 60, as previously, passes through heat exchanger 55 which is made up in the same manner as shown in Fig. 5 and is connected to the upper part of evaporator 30. The arrangement should be such that the 15 level in the U-tube of the reheat-separator is slightly higher than the entrance of conduit 60 into evaporator 30. It will be seen that the connection of conduit 60 with the evaporator determines the pool of liquid 20 maintained in the U-tube. The evaporator is situated within brine tank 83 which brine tank is formed with an enclosure 84' for the insertion of ice trays.

The circulation of absorption liquid between the generator and absorber is substantially like that shown in previous embodiments and like reference characters designate like parts. There is a difference however in that the auxiliary generator is made 25 differently and the heat exchanger is inverted to give a different direction of flow. In this modification, the coil 37 is replaced by a portion of the generator shell 84 surrounding flue 42. A conduit 85 connects 30 this cylindrical auxiliary generator 84 with the upper part of the generator proper. Conduit 36 is connected to auxiliary generator 84 to supply rich absorption liquid thereto. A space 86 is provided at the top of the 35 auxiliary generator by having the lower opening of conduit 85 open into the auxiliary generator some distance below partition plate 87 which separates the generator proper from the auxiliary generator. An 40 improved circulation is obtained with this space over what is obtained without it. Conduit 36 which leaves the lower part of the absorber passes downwardly and circles upwardly towards auxiliary generator 84. 45 Conduit 40, surrounding conduit 36, circles downwardly. By means of this arrangement, any vapor generated in conduit 36 passes upwardly into the auxiliary generator 84.

50 In order to precool the absorption liquid passing into the absorber, conduit 34, in this embodiment, is made to pass through cooling jacket 89 which surrounds the absorber and which is supplied with cooling water. 55 From the absorber jacket 89 the cooling water passes to the condenser jacket 79. Conduit 34 takes several turns through the water within jacket 89 and then enters the upper portion of the absorber.

60 The whole apparatus is mounted on a

plate 88 adapted to form a portion of a refrigerating cabinet.

In Fig. 8 I have shown the reheat-separator applied to an absorption apparatus including a pump. Generator 10 is heated by 70 means of a steam coil 11. Vapor generated in generator 10 passes through conduit 12 and into reheat-separator 20 comprising an outer conduit 13 and an inner conduit 17. The space between conduits 13 and 17 constitute a first path through the reheat-separator which is connected to a separator 90. Separator 90 is connected by means of conduit 14 with a condenser 15. From condenser 15 conduit 91 connects with conduit 17 and liquefied ammonia passes therethrough into the second path of the reheat-separator. From the reheat-separator ammonia passes through conduit 92 and into a second condenser 19 whence it passes 85 through conduit 49 and into evaporator 30. It will be seen that the reheat-separator arrangement is substantially the same as that shown in Fig. 1. A throttling valve 93 is interposed in conduit 49 which valve may be 90 of any construction and which throttles the refrigerant from a high pressure in the generator, reheat-separator and condenser to a low pressure in evaporator 30, the drop in pressure serving to alter the status of the refrigerant thermo-dynamically so that it is forced to evaporate. From evaporator 30 refrigerant passes through conduit 94 and into absorber 31. Absorber 31 is supplied with weak liquor from the generator 100 through conduit 95 in which is interposed a valve 96 for obtaining a drop in pressure between the generator and absorber. A pump 97 serves to pump enriched liquor from the absorber through conduits 98, 99, 105 100 and 101 into the generator. The cooling water jacket for condensers 15, 19 and absorber 31 are suitably interconnected.

While I have described various embodiments of my invention, it will be readily seen that my invention is not limited to particular structure.

It will be obvious that the process improvement of vaporizing a fluid of the system in heat exchange relation with what 115 may be termed a heat rejecting part such as the first path of the reheat-separator may be applied to other heat rejecting parts. It will also be noted that, amongst the functions of the reheat-separator, is that of performing the duty of the part of a refrigeration system known as a rectifier. My reheat-separator is, however, more than a mere rectifier, as the term is defined by prior art and prior usage, particularly in the feature 125 of making the condensation of vapor of absorption liquid leaving the generator properly related to different loads on the system.

What I claim is:

1. Those steps in refrigerating through 130

the agency of an absorption system which consist in generating vapor of a refrigerant, condensing the refrigerant vapor, passing the condensed refrigerant into heat exchange relation with the generated vapor, evaporating condensed refrigerant in said heat exchange relation, recondensing the refrigerant so evaporated, conducting the condensed refrigerant to an evaporating space, providing a pool of liquid in said heat exchange relation and maintaining said pool of liquid due to the supply of condensed refrigerant to said evaporating space.

2. Refrigerating apparatus comprising a generator for expelling a cooling agent from a solution, condensing means for condensing the cooling agent, an evaporator for vaporizing the cooling agent, an absorber for absorbing the cooling agent, means for circulating absorption liquid between the generator and absorber, means to circulate an auxiliary agent between the absorber and evaporator, the parts being connected in open communication to permit the existence of the same pressure throughout the apparatus, a separator interposed between the generator and condensing means, said separator comprising a first path and a second path, so connected that vapor may pass from the generator through said first path and into said condensing means, condensate may pass from said first path back towards said generator, condensate may pass from said condensing means to said second path, condensate may pass from said second path to said evaporator and vapor may pass from said second path into said condensing means and means for establishing a pool of condensate in said second path.

40 3. Refrigerating apparatus comprising a generator for expelling a cooling agent from solution, an evaporator for vaporizing the cooling agent, an absorber for absorbing the cooling agent, the parts being arranged in a system of constant pressure throughout employing an auxiliary agent into which the cooling agent evaporates, said system including also condensing and separating means connected to receive vapor from the generator and return liquid toward the generator, said condensing and separating means comprising a heat exchanger having separated spaces, a condenser, connections for flow of vapor from said spaces to the condenser and means to conduct liquid from one of said spaces to said evaporator and to establish a pool of liquid in said condensing and separating means.

45 4. Refrigerating apparatus comprising a generator for expelling a cooling agent from solution, an evaporator for vaporizing the cooling agent, an absorber for absorbing the cooling agent, the parts being arranged in a system of constant pressure throughout employing an auxiliary agent into which the

cooling agent evaporates, said system including also condensing and separating means connected to receive vapor from the generator and comprising a heat exchanger including a first path, a second path, a condenser connected in series with said paths and a series of baffling members in one of said paths and a connection for conducting liquid from said separator to said evaporator, said connection being arranged to establish a pool of liquid in said condensing and separating means.

5. Refrigerating apparatus comprising a generator for expelling a cooling agent from solution, an evaporator for vaporizing the cooling agent, an absorber for absorbing the cooling agent, the parts being arranged in a system of constant pressure throughout employing an auxiliary agent into which the cooling agent evaporates, said system including also condensing and separating means connected to receive vapor from the generator and comprising a vertically disposed heat exchanger including a first path and a vaporization column and a condenser connected to receive vapor from said first path and said vaporization column and to deliver condensate to said vaporization column and a connection between said vaporization column and said evaporator serving to maintain a pool of condensate in said vaporization column and to conduct condensate to the evaporator.

6. In refrigerating through the agency of an absorption system wherein a refrigerant is vaporized by expelling the same from solution in a generator and carries some vapor of absorption liquid therewith, which refrigerant is liquefied and introduced into an evaporator, that improvement which consists in conducting liquefied refrigerant before introduction into the evaporator back into heat exchange relation with the porous refrigerant carrying vapor of absorption liquid to condense and separate out the vapor of absorption liquid while maintaining the same pressure of the refrigerant expelled by the generator and the liquefied refrigerant conducted back into heat exchange relation therewith.

7. The continuous process of refrigerating through the agency of an absorption system including a generator, an evaporator and an absorber which consists in introducing vaporizable refrigerant into the evaporator, evaporating the refrigerant into an inert gas, conducting the gas mixture thus formed into the absorber, circulating absorption liquid between the generator and absorber to separate the refrigerant from the inert gas in the absorber and convey the refrigerant to the generator, conveying inert gas from the absorber to the evaporator, expelling refrigerant from solution in the generator to obtain gaseous re-

frigerant, liquefying the expelled refrigerant and conducting refrigerant, after liquefaction and before introduction into the evaporator, back into heat exchange relation with the gaseous refrigerant expelled in the generator to condense and separate out entrained vapor of absorption liquid and then introducing the refrigerant into the evaporator.

10 8. In apparatus of the character described, a heat exchanger having separated spaces, means to supply vapor of a volatile fluid containing entrained vaporous solvent to a space of said heat exchanger at a given pressure and to withdraw liquid from said space and means communicating with the aforementioned space to supply liquid of said volatile fluid substantially entirely free from solvent to a second space of said heat 15 exchanger at the same given pressure to cool the vapor of said volatile fluid supplied by the first mentioned means and condense the entrained solvent therein, a liquid receiver other than said generator and means to conduct liquid from said second space to said liquid receiver.

9. A reheat-separator comprising a U-tube, a cylinder surrounding one leg of said U-tube, a gas off-take pipe connected with 20 the other leg of said U-tube, means to withdraw liquid from the bottom of said U-tube, means to withdraw vapor from the top of said cylinder and means to supply liquid to said U-tube, the leg of said U-tube within 25 said cylinder being open.

10. In a device of the character described, a generator, a vertically extending separator comprising a first path and a second path, an upwardly extending conduit from said 40 generator to said separator connected with said first path, a condenser connected to said first path to receive vapor therefrom and connected to said second path to deliver liquid thereto, and means to conduct liquid 45 from said second path outside said generator.

11. In a device of the character described, a generator, a substantially horizontally extending separator comprising a first path and a second path, an upwardly extending conduit from said generator to said separator connected with said first path, a condenser connected to said first path to receive vapor therefrom and connected to said second path to deliver liquid thereto, and means to conduct liquid from said second path outside said generator.

12. In a device of the character described, a generator, a vertically extending separator comprising a first path and a second path, an upwardly extending conduit from said generator to said separator connected with said first path, a condenser connected to receive vapor from both said paths and connected to deliver liquid to said second

path, and means to conduct liquid from said second path outside said generator.

13. In a device of the character described, a generator, a separator comprising a first path and a second path, means to conduct vapor from said generator to said first path and drain liquid into said generator, a condenser connected to said first path to receive vapor therefrom and connected to said second path to deliver liquid thereto, and means to conduct liquid from said second path away from the aforesaid parts.

14. In a device of the character described, a generator, a separator comprising a first path and a second path, means to conduct vapor from said generator to said first path and drain liquid into said generator, a condenser connected to both said paths to receive vapor therefrom and connected to deliver liquid to said second path, and means to conduct liquid from said second path away from the aforesaid parts.

15. In a device of the character described, a generator, a separator comprising a first path and a second path, means to conduct vapor from said generator to said first path and drain liquid into said generator, a condenser connected to said first path to receive vapor therefrom and connected to said second path to deliver liquid thereto, baffle 90 members in said first path, means for conducting liquid from said second path away from the aforesaid parts and means to maintain a pool of liquid in said second path.

16. In a device of the character described, a generator, a separator comprising a first path and a second path, means to conduct vapor from said generator to said first path and drain liquid into said generator, a condenser connected to both said paths to receive vapor therefrom and connected to said second path to deliver liquid thereto, baffle members in said first path, means to conduct liquid from said second path away from the aforesaid parts and means to maintain a pool of liquid in said second path.

17. In a device of the character described, a generator, a vertically extending separator comprising a first path and a second path, an upwardly extending conduit from said generator to said separator connected with said first path, a condenser connected to said first path to receive vapor therefrom and connected to said second path to deliver liquid thereto, a liquid receiver other than said generator, and a liquid conducting conduit connecting said second path with said liquid receiver, said last mentioned conduit establishing a pool of liquid in said second path.

18. In a device of the character described, a generator, a vertically extending separator comprising a first path and a second path, an upwardly extending conduit from said generator to said separator connected with

said first path, a condenser connected to said first path to receive vapor therefrom and connected to said second path to deliver liquid thereto, a liquid receiver other than 5 said generator, a liquid conducting conduit connecting said second path with said liquid receiver, said last mentioned conduit establishing a pool of liquid in said second path, and a gas communication between said second path and said liquid receiver.

19. In a device of the character described, a generator, a vertically extending separator comprising a first path and a second path, an upwardly extending conduit from said 15 generator to said separator connected with said first path, a condenser connected to both said paths to receive vapor therefrom and connected to said second path to deliver liquid thereto, a liquid receiver other than 20 said generator, and a liquid conducting conduit connecting said second path with said liquid receiver, said last mentioned conduit establishing a pool of liquid in said second path.

25 20. In a device of the character described, a generator, a vertically extending separator comprising a first path and a second path, an upwardly extending conduit from said generator to said separator connected 30 with said first path, a condenser connected to both said paths to receive vapor therefrom and connected to said second path to deliver liquid thereto, a liquid receiver other than said generator, a liquid conducting 35 conduit connecting said second path with said liquid receiver, said last mentioned conduit establishing a pool of liquid in said second path, and a gas communication between said second path and said liquid receiver.

40 21. Refrigerating apparatus comprising a generator, a separator, a condenser, an evaporator, an absorber, conduits connecting the aforesaid parts into a system including conduits forming a major circuit for circulation of refrigerant through the generator, separator, condenser, evaporator and absorber, a gas circulation circuit between the evaporator and the absorber, and a liquid 45 circulation circuit between the generator and the absorber, said separator comprising a first path and a second path, said first path being connected to said generator, said condenser being connected between said paths, 50 and said second path being connected to the evaporator, the connection to the evaporator serving to establish a pool of liquid refrigerant in said second path.

55 22. Refrigerating apparatus comprising a 60 generator, a separator, a condenser, an evaporator, an absorber, conduits connecting the aforesaid parts into a system including conduits forming a major circuit for circulation of refrigerant through the generator, separator, condenser, evaporator and absorber, a

gas circulation circuit between the evaporator and the absorber, and a liquid circulation circuit between the generator and the absorber, said separator comprising a first path and a second path, said first path being 70 connected to said generator, said condenser being connected between said paths, and said second path being connected to the evaporator, the connection to the evaporator serving to establish a pool of liquid refrigerant in 75 said second path, and a gas communication between said separator and said gas circulation circuit.

80 23. Refrigerating apparatus comprising a generator, a separator, a condenser, an evaporator, an absorber, conduits connecting the aforesaid parts into a system including conduits forming a major circuit for circulation of refrigerant through the generator, separator, condenser, evaporator and absorber, a gas circulation circuit between the evaporator and the absorber, and a liquid circulation circuit between the generator and the absorber, said separator comprising a 85 first path and a second path, said first path being connected to said generator, said condenser being connected between said paths, and said second path being connected to the evaporator, the connection to the evaporator extending downwardly and again upwardly 90 and having an overflow portion for supplying liquid refrigerant to the evaporator, the height of said overflow portion determining a pool of liquid refrigerant in said second path.

95 24. Refrigerating apparatus comprising a generator, a separator, a condenser, an evaporator, an absorber, conduits connecting the aforesaid parts into a system including conduits forming a major circuit for circulation of refrigerant through the generator, separator, condenser, evaporator and absorber, a gas circulation circuit between the evaporator and the absorber, and a liquid circulation circuit between the generator and the absorber, said separator comprising a first path and a second path, said first path being connected to said generator, said condenser being connected between said paths, 100 and said second path being connected to the evaporator, the connection to the evaporator extending downwardly and again upwardly and having an overflow portion for supplying liquid refrigerant to the evaporator, the height of said overflow portion determining a pool of liquid refrigerant in said second path, and a gas communication between said separator and said gas circulation circuit.

105 25. That improvement in absorption and distillation processes wherein a volatile fluid is expelled from solution in a body of absorption medium of higher boiling point than said volatile fluid, thus forming a vapor mixture consisting of fluids of different boiling points, which consists in cool- 110

130

ing the vapor mixture by condensate of said volatile fluid in heat exchange relation and out of contact therewith to condense the absorption medium constituent of the vapor mixture while maintaining the same pressure of the vapor mixture and the condensate of said volatile fluid to prevent condensation of the vapor of said volatile fluid in the vapor mixture, returning the condensed absorption medium but not the condensate of said volatile fluid to the body of absorption medium and conducting the condensate of said volatile liquid away from the heat exchange relation and away from the body of absorption medium.

26. That improvement in vapor treatment which consists in cooling a binary gas mixture by heat exchange relation with one of the constituents of the mixture condensed and substantially entirely separated from the mixture and in boiling condition to separate by liquefaction a second constituent in the mixture and withdrawing both the one and the second constituents in liquid form from the heat exchange relation.

27. In a device of the class described, a closed member, a U-tube, one leg of said U-tube extending within said member and opening into the upper part thereof, a conduit communicating with the lower part of said member outside of said U-tube, a conduit connecting the upper part of said member with the other leg of said U-tube, means for cooling the last mentioned conduit, and a conduit communicating with the lower part of said U-tube.

28. In a device of the class described, a closed member, a U-tube, one leg of said U-tube extending within said member and opening into the upper part thereof, a conduit communicating with the lower part of said member outside of said U-tube, a conduit connecting the upper part of said member with the other leg of said U-tube, means for cooling the last mentioned conduit, a gas off-take pipe connected with the aforesaid other leg, and a conduit communicating with the lower part of said U-tube.

In testimony whereof I hereunto affix my
signature.

CARL GEORG MÜNTERS.
